UNITED STATES PATENT OFFICE.

JOHN K. PENNINGTON, OF LOS ANGELES, CALIFORNIA.

URINAL.

Application filed January 10, 1922. Serial No. 528,192.

To all whom it may concern:

Be it known that I, JOHN K. PENNINGTON, a citizen of the United States, and a resident of the city of Los Angeles, county of Los Angeles, and State of California, have invented new and useful Improvements in Urinals; and I declare the following to be a full, clear, and exact description of the same.

10 The present invention pertains to urinals, and particularly it has to do with a new and novel means of flushing the same, in a manner to accomplish results in a most complete and sanitary manner.

15 Broadly speaking, I have devised and perfected a new and novel urinal construction, wherein the various component elements are arranged and constructed to accomplish the flushing thereof in a most efficient manner; thereby conducive to purity and sanitation.

20 The merits of my invention will be more fully and completely set forth in the following detailed description, reference being made thereto to the accompanying drawings forming a part thereof, in which I have illustrated the preferred specific form, and in which:

25 Fig. 1 is a front elevation of my improved urinal; Fig. 2 is a plan view thereof, partly in section, being taken as indicated by the line 2—2 of Fig. 1; Fig. 3 is a longitudinal vertical section thereof, taken as indicated by the line 3—3 of Fig. 1; Fig. 4 is 30 an enlarged fragmentary detailed elevation taken as indicated by the line 4—4 of Fig. 3; and Fig. 5 is a fragmentary perspective view showing the manner in which the flushing is accomplished.

35 Referring now to the drawings, numeral 10 designates generally my improved urinal, constructed of any material suitable in such fixtures. It is a type designed to be attached or supported upon a wall surface 11, a short distance above the floor surface, as by means of screws 12 extending through holes in the back or supporting members 13, the latter formed integral with the structure 10.

40 The urinal 10 consists of a main or bowl portion 14 above which flushing tanks 15 are disposed, the whole being formed integral and preferably of the configuration shown in the drawings. The bowl proper 14 has 45 a secondary or smaller bowl portion 16 formed in its bottom for the purpose of re-

taining a certain amount of the flushing water 17 therein at all times. The lower end 18, of a back wall 19, extends down into this bowl portion 16, forming a transverse partition therethrough; in the bottom of which there is an opening or aperture 20, through which the matter contained in the bowl portion 14, forward of the partition 18, is flushed out and into the discharge pipe 21, as indicated by the arrows in Fig. 3 and in the manner to be hereinafter explained.

45 The discharge pipe 21 is also preferably formed integral with the urinal 10, being separated from the bowl portion 16 by its rear wall portion 22, and being formed integral with the back 19 and the bowl portion 16, in the manner best shown in Fig. 3. A clean-out connection, generally designated by the numeral 23, connects the lower end 24, of the discharge pipe 21, with a sewer pipe 25; the latter leading to a sewer or other means of disposal. The clean-out connection 23 will not be herein described in detail, as this member forms the subject-matter of a copending application, filed on the 10th day of January, 1922, Serial No. 528,193. Suffice to say, in this instance, that it forms the connections between the discharge pipes 21 and 25.

50 Side-walls 26 extend rearwardly from the sides of the urinal 10, and terminate at the plane of juncture with the wall surface 11, to completely enclose the rear portion of the urinal. A removable casing member 27 is adapted to be removably attached to the urinal 10, to enclose the clean-out fitting 23; the details of its structure and its manner of attachment being fully set forth in the aforementioned copending application.

55 The urinal is designed to be flushed by a primary flushing tank (not shown) situated above it and connected to it by a downwardly extending pipe 30 extending into an opening 31 in the top of the urinal and rigidly secured therein in any suitable manner, as by means of a union 32. Secondary flushing tanks 15 are situated above the bowl 14, two of them being provided—one on either side of the center—and preferably formed integral with the bowl structure, alt in the manner shown. These tanks may be formed in any suitable configuration, that shown in the drawings being preferable. They are spaced apart to form a vent cham-

ber 33 between them, and which continues out through the back 19, in the form of a neck 34, which may be thereafter connected to a suitable vent tube.

5 The pipe 30, through the opening 31, discharges into a chamber 35, which chamber, at either end, connects with the secondary flushing tanks 15 through openings 36. In this manner water is supplied by the 10 primary flushing tank overhead, through the chamber 35, openings 36, and into the secondary flushing tanks 15 at the time the primary flushing takes place. Openings 36 are the only openings in the secondary 15 flushing tanks 15, except orifices 37, adjacent the bottoms thereof, and openings 42, the functions of which will be hereinafter explained.

10 The outer and upper edge 40, of the bowl 14, is rolled to form a tubular conduit 41, which conduit continues around the edge of the bowl and on upwardly through the secondary flushing tanks 15 (see Fig. 2, and dotted lines in Fig. 1), to openings 42 in 15 the chamber 35. From the chamber 35, at the time of the primary flushing of the urinal, water is also supplied to the conduit 41 for flushing the bowl 14, through a plurality of small perforations 43, extending through the underside of the conduit wall. Thus when water is supplied 20 to the conduit 41 the sides of the bowl 14 are washed and flushed by the water flowing through the perforations 43, in the 25 manner indicated by the arrows in Fig. 3.

It will be noted that from about the bottom 15^a, of the secondary flushing tanks 15, the rear wall 19 of the urinal is inclined outwardly and terminates by juncture with the bottoms of the bowl portions 14 and 16. The reason for this is that when water is directed downwardly over the outer face of this rear wall portion 19, in the manner to be described, it will have 30 a tendency, superinduced by the particular form of elements included, to spread out and flow over this surface for accomplishing its flushing in the most efficient manner.

35 In connection with the last mentioned proposition, I form two channels 45 preferably integral with the back 19, and extending from a juncture with the inner faces 15^b, of the secondary flushing tanks 15 outwardly towards the center and terminating to leave a small space between their contiguous ends. These channels 45 extend from the orifices 37 (which extend through walls 15^b of the tanks 15) and are inclined very slightly downwardly towards 40 their outer ends, to conduct flushing water, discharged through the orifices 37, to the center of the rear wall 19 and between the adjacent ends of the channel members. It will be noted that the orifices 37 discharge 45 directly into the bottoms of the channels

45; the latter being curved slightly in their bottoms to properly conduct the water. The channels 45 are so formed, as to present inner adjacent faces 46, which faces taper downwardly and merge into the rear wall 19. The faces 46 are slightly curved as to diverge as they extend downwardly, in order that the water carried by the channels 45 and discharged between the faces 46, will have a tendency to spread outwardly and 50 not be limited thereby.

55 A diverging or spreading portion 47 is likewise formed integral with the back 19 and is in the configuration of an inverted V-shaped convex member, with its apex extending upwardly and terminating at a point between the lower ends of the tapered faces 46. The portion 47 is so formed that at its apex 48 and along its inclined sides 47^a it merges into the outer face of the rear wall 19, inclining outwardly therefrom towards its bottom in the manner clearly illustrated in Fig. 5. The lower diverging ends of the portion 47 terminate at the sides of the discharge opening 20 in the wall 19. 60 The extent to which the sides 47^a of the portion 47 flare outwardly may be altered to suit circumstances, depending on the volume of water discharged through the orifices 37 and flowing down over the outer face of the 65 wall 19.

70 Under ordinary circumstances, the individual will direct the stream of urine against or adjacent the face of the spreader 47, and it is for this reason that the flushing will be most efficient. When the major flushing takes place, either automatically or by hand in the usual manner, the water flowing through the pipe 30, and into the chamber 35, will flow through both the openings 36 and 42, filling the secondary flushing tank 15 and at the same time directing a stream of water through the conduit 41, which flushes the bowl 14 through the perforations 43 at 75 the same time the tanks 15 are filling up. From the time the water first flows into the tanks 15, through the openings 36, it will pass outwardly through the small orifices 37, along the channels 45, and flow downwardly over the face of the wall 19, between the faces 46, where it will have a tendency to spread out in the manner illustrated in Fig. 5, and where it will be further spread by the spreader 47. This stream of water 80 will have a tendency to bunch as it flows between the faces 46, but upon striking the apex 48 of the spreader 47 it will be deflected and spread out over its convex inclined face as it flows toward the opening 20, 85 in the manner illustrated in Fig. 5.

90 The flushing of the bowl 14 will of course take place first and this flushing will cease at the time water ceases to flow into the chamber 35; but the tanks 15 being filled, and the orifices 37 being quite small, water 95

will continue to flow over the face of the wall 19, in the manner hereinbefore described, for several minutes after the primary flushing has taken place, thus tending to very efficiently and thoroughly flush the surfaces of the wall 19 and the spreader 47.

Not only does the arrangement of the water conducting and diverting elements on the face of the wall 19, as hereinabove described, tend to spread the water out and thoroughly cleanse the surfaces, but it prevents water flowing thereover in such a stream as to deposit metallic substances thereon and stain the surface of the fixture, as is commonly the case.

While I have herein described the preferred embodiment of my invention, it is nevertheless to be understood that I reserve the right to make any changes or modifications in the structure which properly come within the scope of the appended claims.

Having described my invention, I claim:

1. The combination with a primary flushing water supply means, a urinal having a bowl, said bowl having a back wall, a secondary flushing tank above said bowl, water supply connection between said primary supply and secondary tank, means in connection with said primary supply and secondary tank and bowl to effect a primary flushing of the bowl, means in connection with said secondary tank to effect a protracted flushing of the bowl continuing after said primary flushing, and means in connection with the back wall of the bowl to distribute said secondary flushing over its surface.

2. In a fixture of the class described, a bowl, and a back wall, primary flushing

water supply means therefor, means to direct a part of the flushing water directly to the bowl, a reservoir connected with the primary supply to be filled with another part of the water during the flushing action, and a restricted outlet for the reservoir discharging onto the back wall to prolong the discharge of water over the back wall after the flushing operation is completed.

3. In a urinal, a bowl having a back wall, flushing means comprising two water feeds at opposite sides of the back wall directing two streams of water toward the central part of the bowl, means to carry the two water streams to the central part of the bowl to meet there, and a spreader on the back wall below the point of stream meeting.

4. In a urinal, a bowl, and two flushing tanks arranged at opposite sides of the upper part of the bowl with a ventilation passage between them.

5. In a urinal, a bowl with a back wall, two flushing tanks arranged at opposite sides of the upper part of the wall with water outlets directing two water streams inwardly toward each other to meet near the central part of the back wall, and with a ventilation passage between the two tanks.

6. A device of the character described, having a bowl and a back wall, means for flushing both the bowl and back wall, said means including a means for protractedly directing flushing water against the back wall for a time after flushing of the bowl is completed.

In witness that I claim the foregoing I have hereunto subscribed my name this 20th day of December, 1921.

JOHN K. PENNINGTON.
